UNITED STATES PATENT OFFICE.

FRANK A. ALLEN, OF JACKSON, MICHIGAN.

DESIGN FOR AN INDEX AND CARD HOLDER.

SPECIFICATION forming part of Design No. 25,317, dated March 31, 1896.

Application filed February 29, 1896. Serial No. 581,407. Term of patent 14 years.

To all whom it may concern:

Be it known that I, FRANK A. ALLEN, a citizen of the United States, residing at Jackson, in the county of Jackson and State of Michigan, have invented a new and original Design for Index and Card Holders, of which the following is a specification.

This invention relates to a new and original design for index-card holders; and it has for its object to provide a design of this character that shall be both useful and ornamental.

The leading feature of the design resides in a rectangular body-plate angled at an intermediate point to form a lower vertically-disposed portion and an upper approximately horizontal portion, which latter portion of the body-plate is provided with a flange extension disposed at an obtuse angle thereto, said lower vertical portion of the body-plate having an upturned sigmoidal-shaped flange extension bounding with said vertical portion a substantially U-shaped figure.

In the drawings, Figure 1 is a perspective view of an index-card holder embodying the herein-described design. Fig. 2 is an end view hereof.

Referring to the accompanying drawings, the numeral 1 designates a rectangular body-plate angled at an intermediate point, as at 2, to form a lower vertically-disposed portion 3 and an upper approximately horizontal portion 4. The portion 4 of the body-plate is provided at one edge with a flange extension 5, disposed at an obtuse angle to said portion 4, and said vertical portion 3 of the body-plate is provided with an upturned sigmoidal-shaped flange extension 6, which, together with the said vertical portion 3, bound a substantially U-shaped figure 7.

What I claim is—

The design for an index-card holder herein shown and described.

In testimony that I claim the foregoing as my own I have hereto affixed my signature in the presence of two witnesses.

FRANK A. ALLEN.
